FLUID PRESSURE TOOL

Filed Oct. 16, 1929

BY

Ira L. Nickerson
ATTORNEY.

UNITED STATES PATENT OFFICE

GUSTAVE M. NELL, OF DETROIT, MICHIGAN, ASSIGNOR TO CHICAGO PNEUMATIC TOOL COMPANY, OF NEW YORK, N. Y., A CORPORATION OF NEW JERSEY

FLUID PRESSURE TOOL

Application filed October 16, 1929. Serial No. 399,888.

This invention relates to fluid pressure tools of the percussive type having automatically thrown valves for controlling the distribution of motive fluid. In certain respects it may be considered as an improvement upon, or further development of, the invention disclosed in my copending application Serial No. 314,893, filed October 25, 1928, issued as Patent No. 1,796,389 on March 17, 1931.

Among the objects of the invention are to increase the positiveness of actuation of the moving parts in tools of the described type, to cause the hammer piston to have a long or full rear stroke with a minimum amount of motive fluid, to increase the rotational torque in rifle bar rotation machines or tools, and in general to improve prior tools and to increase their efficiency.

In order to illustrate the invention one concrete embodiment thereof is shown in the accompanying drawing in which:

Fig. 1 is a longitudinal sectional view;

Fig. 2 is a fragmentary sectional view on an enlarged scale of the tool shown in Fig. 1 with the valve and piston in different positions;

Fig. 3 is a left-end elevational view, on the scale of Fig. 1, of the cylinder with the backhead and the cylinder ring removed.

The embodiment of the invention chosen for the purpose of illustration comprises a pneumatic percussive tool having a cylinder 4 providing a piston chamber within which reciprocates an impact member or piston 5 arranged to impart blows to a working tool, such as a drill steel 6, supported in a rotary chuck 7 mounted in front head 8 secured to cylinder 4. Cylinder 4 is provided with an exhaust chamber formed by a transverse annular groove 9 substantially centrally of the piston chamber and communicating directly with atmosphere through one or more ports 10. This exhaust chamber is controlled by piston 5 and is arranged to be overrun by the latter in both directions.

A rotary impulse is imparted to piston 5 during its reciprocations by conventional mechanism comprising a rifle nut 11 supported in the recessed portion of piston 5 and slidably receiving a rifle bar 12 having ratchet mechanism supported in back head 13, the rifle bar projecting through and having a bearing in cylinder ring 14 which is held in place by back head 13. Piston 5 has a fluted or ribbed extension 5a for transmitting the rotary impulse of the same to chuck 7.

Cylinder 4 also provides a valve chamber in which is disposed an automatically thrown valve 15 arranged to move in timed relation with piston 5 and to control the distribution of motive fluid from inlet 16 to opposite ends of the piston chamber to drive the piston in both directions. Valve 15 is of substantial length and is disposed in parallelism with the piston chamber and closely adjacent thereto so that the connecting ports and passages are relatively short and direct.

Motive fluid for driving the piston on its working stroke (Fig. 1) enters the piston chamber by a port 17a from chamber 17 under control of the rear end of the valve and motive fluid for the return stroke (Fig. 2) passes axially through the bore of valve 15, thence transversely into valve chamber 18 axially through passages 19 to chamber 20 and thence through a port 20a directly into the piston chamber. The ends of valve 15 are differential in size thereby providing differential pressure areas, the smaller area 21 being at the left or rear end of the tool and the larger area 22 being at the forward end. A shoulder 21a adjacent the small end of the valve and always in communication with the rear end of the piston provides a compression area subjected to air trapped and compressed by the piston to shift the valve to the forward position (Fig. 1). Near the compression area 21a valve 15 has an external enlargement or flange 23 providing a shift area 24 in chamber 25, which area is opposed to areas 21 and 21a and is greater than the sum of the latter. Both faces of flange 23 are continuously vented to atmosphere, the rearward face by a large vent 26 and shift area 24 by a restricted vent 27. A passage 28 extends from valve area 24 to the piston chamber under control of piston 5 for admitting pressure fluid to shift the valve rearwardly.

By reason of restricted vent 27, passage 28 also vents to a limited extent and for a slight interval the rear end of the piston chamber on the rearward stroke of the piston (Fig. 2). On the forward stroke of the piston (Fig. 1) there is an auxiliary exhaust for the front end of the piston, this exhaust utilizing main exhaust chamber 9 and being under control of valve 15, the air ahead of 10 the piston passing out through inlet port 29a, chamber 20, axial passage 19, valve chamber 18, around and along an exterior groove 29 in the valve to valve chamber 30 and thence by a passage 31 to exhaust chamber 9. The 15 fluid pressure tool, as heretofore described, is similar, so far as piston and valve operation is concerned, to that disclosed in my aforesaid copending application, Serial No. 314,893, filed October 25, 1928, and the cycle 20 of operation is identical.

To secure full efficiency of the tool and to provide for a powerful piston blow and strong and positive rotation of the drill steel when rifle bar mechanism is used, as herein 25 shown, it is important that the piston be caused to make a long rearward stroke under any conditions of operation. To those skilled in this art, it is a well known fact that in the type of mechanism shown, under heavy rotational load on the rotation train, there is a 30 tendency for the piston to short stroke or "flutter" with high mean effective pressure on both sides of the piston and loss in rotative power, unless a special provision is made to 35 avoid same. To this end an additional vent is provided for the rear end of the piston chamber during the back stroke of the piston to delay the trapping of air in the rear end of the piston chamber and the consequent 40 early shifting of the valve through the building up of pressure against compression area 21a on the valve. This auxiliary vent comprises a port 33 opening into the rear piston chamber intermediate shift passage 28 and 45 inlet port 17a. Vent port 33, which is controlled by piston 5 communicates, as indicated, by passage 33a with valve chamber 34, which chamber, in the rearward position of the valve (Fig. 2) is placed in communication 50 with exhaust valve chamber 30 by annular groove 29 in valve 15 with the result that this auxiliary vent is closed when the valve is in its forward position (Fig. 1) for the power or working stroke of the tool. Through 55 the connection of exhaust chamber 30 around the valve by passage 31 with main exhaust chamber 9 of the cylinder, it will be evident that the fluid vented through auxiliary vent port 33 passes to atmosphere through main 60 cylinder exhaust 9 and atmospheric ports 10.

While the invention has been herein disclosed in what is considered to be its preferred form, it is to be understood that the invention is not limited to the specific 65 details thereof, but covers all changes, modifica-

tions, and adaptations within the scope of the appended claims.

I claim as my invention:

1. In a fluid pressure motor, a cylinder providing a piston chamber, a piston reciprocable therein, a fluid pressure valve, one end of which controls admission of fluid pressure to one end of said piston chamber and the other end of said valve to the other end of said piston chamber, said valve having only one compression area constantly in communication with one end of said piston chamber and a shift area opposed to said compression area, means intermittently bringing said shift area into communication with said piston chamber including a port controlled by said piston, a continuously open vent for said shift area, and means intermediate said port and said end of said piston chamber providing an additional vent under control of said piston and of said valve and operable only after movement of said valve by action of pressure fluid on said shift area.

2. In a fluid pressure motor, a cylinder providing a piston chamber, a piston reciprocable therein, a fluid pressure valve, one end of which controls admission of fluid pressure to one end of said piston chamber and the other end of said valve to the other end of said piston chamber, said valve having only one compression area constantly in communication with one end of said piston chamber and a shift area opposed to said compression area, means intermittently bringing said shift area into communication with said piston chamber including a port controlled by said piston, a continuously open vent for said shift area, and venting means for said end of said piston chamber controlled by said valve and including a port intermediate said first named port and said end of said piston chamber for effecting a predetermined delay in the shifting of the valve under compression, said last-named venting means being operable subsequent to movement of said valve by pressure fluid admitted through said first-named port against said shift area.

3. In a fluid pressure machine for rotating and imparting blows to a working tool, a cylinder providing a piston chamber, a piston reciprocable therein, an automatically thrown valve controlling with its ends the admission of motive fluid to the opposite ends of said piston chamber, means for rotatably supporting the working tool in position to receive the blows of said piston, rotation mechanism for said tool actuated by the reciprocations of said piston, said valve having a compression area constantly in communication with one end of said piston chamber and a shift area opposed to said compression area, means intermittently bringing said shift area into communication with said piston chamber including a port controlled by said piston, a continuously open vent for said shift area

serving as an auxiliary exhaust for the piston chamber on movement of said piston in one direction, and means intermediate said port and said end of said piston chamber under control of both said piston and said valve to provide an additional vent for insuring a substantially full stroke of said piston in said direction.

4. In a fluid pressure machine for rotating and imparting blows to a working tool, a cylinder providing a piston chamber, a piston reciprocable therein, an automatically thrown valve controlling with its ends the admission of motive fluid to the opposite ends of said piston chamber, means for rotatably supporting the working tool in position to receive the blows of said piston, rotation mechanism for said tool actuated by the reciprocations of said piston, said valve having a compression area constantly in communication with one end of said piston chamber and a shift area opposed to said compression area, means intermittently bringing said shift area into communication with said piston chamber including a port controlled by said piston, a continuously open vent for said shift area serving as an auxiliary exhaust for the piston chamber on movement of said piston in one direction, and additional venting means under control of both said piston and said valve for said end of said piston chamber.

Signed by me at Detroit, in the county of Wayne and State of Michigan this 10 day of October, 1929.
